(57) **CLAIM**

The ornamental design for a drink bottle as shown and described.

DESCRIPTION

FIG. 1 is a top perspective view of a drink bottle; FIG. 2 is a bottom perspective view of the drink bottle of FIG. 1;

FIG. 3 is a front view of the drink bottle of FIG. 1;

FIG. 4 is a rear view of the drink bottle of FIG. 1;

FIG. 5 is a left view of the drink bottle of FIG. 1;

FIG. 6 is a right view of the drink bottle of FIG. 1;

FIG. 7 is a top view of the drink bottle of FIG. 1; and,

FIG. 8 is a bottom view of the drink bottle of FIG. 1.

In the drawings, the broken lines are included to illustrate portions of the drink bottle or the environment of the drink bottle that form no part of the claimed design.

1 Claim, 8 Drawing Sheets
